(57) **CLAIM**

The ornamental design for a multi purpose tool set with data memory device resembling military identification tags, as shown and described.

DESCRIPTION

FIG. 1 is a perspective view of the multi purpose tool set with data memory device resembling military identification tags connected with an optional chain that is shown in broken lines.

FIG. 2 is a front view of the memory device within a bay resembling a military identification tag, and a top view of the multi purpose tool.

FIG. 3 is a side view of the memory device and the multi-purpose tool.

FIG. 4 is a top view of the memory device and the multi-purpose tool.

FIG. 5 is an exploded perspective view of the data memory device and the matching bay shown separately for ease of illustration; and,

FIG. 6 is an exploded perspective view of multi purpose tool, showing the tools in a position of use and shown separately for ease of illustration.

The broken lines shown in the drawings form no part of the claimed design.

The figures describe the combination of a multi purpose tool and a data memory device residing in a matching bay, where the bay and the multi-purpose tool are made to resemble common military identification tags.
